UNITED STATES PATENT OFFICE.

POWEL CROSLEY, JR., OF CINCINNATI, OHIO.

ADAPTER.

Application filed October 9, 1922. Serial No. 593,404.

My invention relates to electrical conductors, and more especially to socket adapters; its object being, as herein exemplified, to permit the use of a certain audion 5 or vacuum-tube detector or amplifier, in a receptacle or socket made for a different kind of device of that character, in radio installations. A further object is to provide an extremely simple and inexpensive, yet reliable device of this character, proof against wrong connection of the instrument connected by it, and easy to insert or remove from the apparatus. Other objects will appear in the course of the ensuing description.

10 I attain these objects by the device illustrated, for example, in the accompanying drawing, in which—

Figure 1 is a partial side elevation of an adapter embodying my invention, with one 20 of the vacuum tubes mounted therein, and the adapter mounted in one of the sockets, this socket being in front-to-rear cross-section on a vertical plane through the center thereof, and only part of the vacuum tube being 25 shown, for lack of space;

Fig. 2 is a bottom plan view of the socket with the adapter therein;

Fig. 3 is a similar view of the adapter removed from the socket;

30 Fig. 4 is a top plan view of the adapter;

Fig. 5 is a vertical cross-section on the planes of the broken line 5—5 of Fig. 3;

Fig. 6 is a similar section on the plane of the line 6—6 of Fig. 3;

35 Fig. 7 is a detail perspective view of one of the bushings;

Fig. 8 is a bottom plan view of the adapter body without the contact elements mounted thereon, better showing the arrangement and 40 form of the openings therein;

Fig. 9 is a detail perspective view of one of the protruding contact elements;

Fig. 10 is a similar view of one of the yielding contact elements;

45 Fig. 11 is a similar view of the connector; and

Fig. 12 is a perspective view of the base of the vacuum tube.

The body 1 is cylindrical, and preferably 50 made of insulating material throughout such as hard rubber, fiber or composition of other suitable kind. It has, at one side, near its top, a radially extending engaging element in the form of a pin 2; and the socket 3 into which 55 the adapter is introduced (Figs. 1 and 2) has a cylindrical interior fitted snugly by

the cylindrical body 1, and has near its top a bayonet slot 4 which forms an engaging means on this socket for engagement of the means 2 of the adapter to hold the adapter 60 down in the socket, and also serving to compel insertion of the adapter into the socket in correct relation thereto to make the correct electrical connections as will be described. 65

The particular socket herein disclosed is fully disclosed and claimed in my co-pending application, Serial No. 520,644, filed December 7, 1921.

The vacuum-tube or audion 5 is one recently introduced on the market by a well known manufacturer, and has, instead of the four contact elements in a single plane, as found in many other devices of this character, which would contact with the four similarly arranged contact blades 6 of the above socket, three protruding contact elements 7 and a fourth protruding contact element 8, longer and thicker than the first three. Also, 70 these contact elements are not arranged in the same order, with respect to the plate and grid and the two filament ends of the audion tube, as in the other tubes for which the disclosed socket primarily is designed. These protruding contact elements 7 and 8 are 75 designed to enter apertures of corresponding width and relative location, in a socket designed for these tubes; and the difference in thickness of the one element 8 from the others compels the correct application of the 80 tube to its socket. Its greater length also contributes to this, as well as facilitates the application, since this longer element can be partly inserted in its aperture before the others begin to enter theirs. Friction between these protruding contact elements and 85 suitable resilient contact elements in the socket designed for them, serves to hold the tube in the socket or mounting; and it has no projection to engage with a bayonet slot 90 such as that in the socket herein disclosed. 95

Accordingly, my adapter body 1, with the projection 2 to correctly engage in the bayonet slot, has through it, parallel with its cylindrical axis, three apertures 9, and a fourth wider aperture 10. The projecting contact elements 7 and 8 of the tube 5 being cylindrical, these apertures 9 and 10 are cylindrical also, and of diameter to receive the elements 7 and 8, respectively, easily but 100 snugly, with the bottom of the tube base 11 resting snugly on the top of the adapter body 105

110

1, and the elements 7 and 8 extending only part way lengthwise through the body 1, as seen in Fig. 1. The central recess 12 in the top of the body 1 receives a central projection 12' which the tube base 11 has.

The contact blades 6 of the socket 3 are flat strips secured in transverse recesses 13 in the bottom of the socket base, by small bolts 14 which serve as the terminals of this 10 socket as fully set forth in the aforementioned copending application. These blades 6 bend slightly upward in their extension in toward the front-to-rear center line of the socket or receptacle 3, where their inner ends 15 are materially separated, as seen in Fig. 2, and yield down, with resilience, to contact elements of a device mounted in the socket, such as the tubes for which the socket is especially designed.

20 To make contact with these blades 6, my adapter has the four protruding contact elements 15 on its bottom, offset from the apertures 9 and 10 thereof in such degree as is necessary for them to have the symmetrical arrangement of the socket blades 6 while the apertures have the asymmetrical arrangement called for by the mentioned audion tube.

The body 1 being of a non-metallic material, it has sockets formed in it at the locations for the elements 15, in which sockets are embedded small metallic bushings 16 (Fig. 7) which may be forced in, or may be molded in place if the body 1 is molded.

35 To insure their maintenance in these sockets, the bushings 16 preferably are knurled or otherwise roughened on their sides, as shown. Each bushing is tapped interiorly; and each protruding contact element 15 has a reduced 40 part or shank 15' threaded into a respective bushing, with a shoulder 17 at the end of the threaded reduced part or shank 15' where it joins the unreduced part, which preferably is cylindrical.

45 On account of the different relative arrangement of the connections in this audion tube, the connections can not be made in regular order, as before alluded to. To provide the correct modified order of arrangement, a fifth bushing 16' exactly like the bushings 16 just described, is set into a socket in the bottom of the body 1 in the same way that the others are; being located radially inward, near the center of the body 50 bottom, next to one of the smaller apertures 9 which is next in order to the odd large aperture 10.

55 Each aperture 9 and 10 has along one side, from the bottom of the body, not quite up to the top of the body, a channel 18 or 19, respectively, flat sided, and, with the exception of the channel 18 of the smaller aperture 9 with which the fifth bushing 16' is provided, these channels are located over next 60 to a corresponding adjacent bushing 16 in

direction clock-wise therefrom, looking from the top (Fig. 4) and of course appearing in the opposite relation in the bottom views, Figs. 2, 3 and 8. The channel of the excepted fourth aperture 9 is over toward the 70 associated fifth bushing 16'.

These channels afford spaces for the yielding contact elements 20, which are all alike; the channels 18 and 19 all being the same width, which, preferably is the diameter of 75 the smaller apertures. The channel 19 of the large aperture 10 thus is narrower than the aperture, as seen, which is immaterial to the correct working of the device. Each element 20 is a thin flat metal strip bent with 80 a foot or extension 21, the main longer part having a compound curve in its upper half so that it presents a convexity 22 to lie in against the flat bottom of the respective channel, and an intermediate convexity 23 85 in the other direction, to extend out into the respective aperture until the contact element or prong of the audion tube is inserted, whereupon it yields back into the channel, but presses firmly out against the prong. 90 From this intermediate convexity down to the junction with the foot 21, the element is substantially straight; and when pressed back as just mentioned, this straight lower part will lie firmly against the side of the audion tube prong 7 or 8, making efficient 95 electrical contact.

On account of the asymmetrical arrangement of the apertures and the symmetrical arrangement of the bushings and protruding contact elements at the bottom of the adapter, it will be seen that some of these are 100 farther apart than others. So that the yielding elements may be all alike, yet provide for this, the feet 21 have elongated slots 21' (Fig. 10) receiving the shanks 15' of the protruding elements 15, which thus extend through these feet into the respective bushings 16, with the shoulders 17 clamping the 105 feet 21 in firm electrical connection directly with three of these elements 15. The fourth protruding element 15 is connected, across the body bottom, with the foot 21 of the fourth yielding element 20, by a connector 24, a flat thin metal strip with holes near opposite ends (Fig. 11) one of which receives the shank 15' of the element 15, and the other receiving a small screw 25 through it and the slot of the foot 21, clamping these together by screwing into the fifth bushing 110 16'; the connector 24 lying outside the foot 21 and having a slight bend to go behind the shoulder of the contact element 15 at the other end.

The protruding contact elements 15 are 115 made long enough to space the bottom of the adapter body amply far up from the socket or receptacle blades 6, so that there is no chance of contact of these with any intermediate conducting parts, as the connector 120 130

or its screw 25. The channels of the apertures terminating short of the top of the body 1, these apertures present circular openings at the top, preserving their properties as guides and holders for the audion tube prongs; below which, along the channels, the firm contact of the elements 20 contributes to this guidance and holding in an efficient manner. The yielding elements 20 having their upper free ends curved out under the upper terminations of the channels, are protected thereby, so that the incoming prong ends cannot engage with the ends of these elements and bend or disrupt them. Thus the only exposed parts, such as the protruding elements 15 at the bottom, and the lateral engaging pin 2, are rigid and substantial; and the entire device presents, exteriorly, a simple and neat appearance and involves, at no place, any great complication.

Having fully described my invention, what I claim as new and desire to secure by Letters Patent is:

1. In an adapter, a body having apertures from end to end, each with a channel along one side, yielding contact elements in the respective channels, insulated from each other and lying partly in the respective apertures to be forced therefrom by the prongs of an electrical instrument inserted into the respective apertures, and protruding contact elements on one end of said body, offset from the apertures, insulated from each other, and electrically connected to the respective yielding contact elements.

2. In an adapter, a body having apertures from end to end, each with a channel along one side opening through one end of said body but not through the other end thereof, yielding contact elements in the respective channels, insulated from each other and lying partly in the respective apertures to be forced therefrom by the prongs of an electrical instrument inserted into the respective apertures from said other end, and protruding contact elements on the one end of said body, offset from the apertures and insulated from each other, each yielding contact element having an extension from the open end of the respective channel, electrically connected to a respective protruding contact element.

3. In an adapter, a body having apertures from end to end, each with a channel along one side opening through one end of said

body but not through the other end thereof, yielding contact elements in the respective channels, insulated from each other and lying partly in the respective apertures to be forced therefrom by the prongs of an electrical instrument inserted into the respective apertures from said other end, protruding contact elements on the one end of said body, offset from the apertures and insulated from each other, each yielding contact element having an extension from the open end of the respective channel, one of said protruding contact elements being remote from its respective aperture and yielding contact element, and a connector electrically connecting the extension of this yielding contact element to this remote protruding contact element across the surface of said one end of said body, the extensions of the other yielding contact elements being electrically connected to their respective protruding contact elements.

4. In an adapter, a body of insulating material having apertures from end to end, each with a channel along one side opening through one end of said body but not through the other end thereof, yielding contact elements in the respective channels, lying partly in the respective apertures to be forced therefrom by the prongs of an electrical instrument inserted into the respective apertures from said other end, bushings embedded in said one end of said body, offset from the apertures, an additional bushing embedded in said one end of said body, near one of the apertures, each yielding contact element having an extension from the open end of the respective channel, the extension from the channel of the one aperture electrically contacting with said additional bushing, and the extensions of the other yielding contact elements electrically contacting with respective adjacent bushings, protruding contact members in these adjacent bushings, clamping the extensions to the bushings, a connector extending directly from the additional bushing, across the surface of said one end of said body, to a remaining adjacent bushing, a protruding contact member electrically connecting with this connector and clamping it to said remaining bushing, and a screw in said additional bushing, clamping said connector and the respective extension to said additional bushing.
